(57) **CLAIM**

The ornamental design for a loudspeaker, as shown and described.

DESCRIPTION

FIG. 1 is a front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8 is a cross-sectional view thereof, taken along line 8-8 of FIG. 2; and,

FIG. 9 is a cross-sectional view thereof, taken along line 9-9 of FIG. 2.

The broken lines illustrate portions of the loudspeaker that form no part of the claimed design. The shading is provided merely to represent contours of the design and does not connote the character of the surfaces such as any specific
